UNITED STATES PATENT OFFICE.

HERMAN SACKS, OF CHICAGO, ILLINOIS.

SLEEVE-PROTECTOR.

No. 925,952.

Specification of Letters Patent.

Patented June 22, 1909

Application filed August 11, 1908. Serial No. 447,962.

To all whom it may concern:

Be it known that I, HERMAN SACKS, a citizen of the United States, residing at Chicago, in the county of Cook and State of Illinois, have invented certain new and useful Improvements in Sleeve-Protectors, of which the following is a specification.

My invention relates in general to protectors for sleeves, and more particularly to an adjustable protector.

In the use of protectors to prevent the soiling of sleeves it is desirable that they should fit closely around the forearm of the wearer. It is, therefore, necessary that the protectors should vary in size according to the various sizes of the forearms of the users, which requires that protectors should be made in a large number of different sizes.

The primary object of my invention is to provide a sleeve protector which may be readily adjusted in size to fit different sizes of forearms, thereby rendering it possible to use the same protector on different sizes of forearms.

A further object of my invention is to provide a sleeve protector which will be simple in construction, inexpensive in manufacture, and efficient in use.

My invention will be more fully described hereinafter with reference to the accompanying drawings in which the same is illustrated as embodied in several convenient and practical forms, and in which—

Figure. 1 is a perspective view; Fig. 2 a transverse sectional view of the form of my protector shown in Fig. 1; Fig. 3 a perspective view of a modified form; Fig. 4 a sectional view on line 4, 4 Fig. 3 of the modified form of my invention; Fig. 5 a plan view; and Fig. 6 an end elevation of still another embodiment of my invention.

Similar reference characters are used to designate similar parts on the several sheets of drawings.

Referring more particularly to Figs. 1 and 2, reference character A indicates a sleeve protector comprising a sheet of flexible material of any suitable character, which is adapted to be wrapped around the forearm of a wearer with its edges overlapped.

B, B designate straps of suitable flexible material, each of which is secured at one end to the edge of the underlying portion of the protector. Each of the straps B passes through and is adjustably held by a device

C secured to the overlapping portion of the protector adjacent its edge.

c indicates one member of a fastening device which is adapted to removably engage the other member a of the fastening device, the latter member being rigidly secured to the flexible material of the protector A at a distance from the underlying edge equal to the length of the strap. While I have shown two straps B, yet it is obvious that a single strap and coöperating parts might be used, or that more than two of such straps might be employed.

The manner of using the form of my protector above described is as follows: Each of the straps B is adjusted relatively to the holding device or slide C so that when the members c and a of the fastening device are engaged the protector will have the desired size. The size of the protector may be readily varied by adjusting the position of each of the straps relatively to the holding device or slide C.

In Figs. 3 and 4 I have shown a modified form of my invention in which B¹, B¹ indicate straps secured at their ends to the underlying portion D¹ of the protector A¹. A slide C¹ adjustably engages each of the straps B¹ having thereon one member c¹ of a two-part fastening device, the other member a¹ of the fastening device being secured adjacent the edge of the overlapping portion of the protector. In order to vary the size of this form of my invention it is merely necessary to adjust the slide C¹ relatively to the strap which it engages, thereby varying the position of the member c¹ of the two-part fastening device relatively to the edge of the underlying portion of the protector.

In Figs. 5 and 6 I have illustrated still another form of my invention in which straps B², B² are secured at their ends to the underlying portion D² of the protector, which latter is made separate from the main portion A² of the protector. Each of the straps B² passes through and adjustably engages a holding device or slide C² secured adjacent one edge of the protector. Supported upon the end of each strap B² is one member c² of a two-part fastening device, the other member a² thereof being secured adjacent the opposite edge of the protector from that to which the slides C² are secured. In the use of this form of my invention the straps B² may be adjusted relatively to the

respective holding slides C², thereby varying the distances of the members c² of the two-part fastening devices from the edge of the protector in which the slides C² are secured.

In each of the several forms of my invention above described, it will be observed that a relative adjustment of a strap and engaging retaining slide varies the distance of one member of a two-part fastening device from one edge of the protector, thereby varying the size of the protector to fit various sizes of forearms.

While I have illustrated my invention as embodied in three different forms, yet it will be evident that it may be embodied in other forms and that my invention is not limited in scope to the several embodiments thereof which I have illustrated and described.

20 I claim:

1. In a sleeve protector, the combination with a piece of flexible material adapted to be wrapped around the forearm of the wearer, of a transverse strap overlying and secured to the underlying portion of the protector, a fastening member carried by said strap, a coöperating fastening member secured to the protector, and means adjustably engaging the strap for varying the position of the fastening member thereon relatively to an edge of the protector.

2. In a sleeve protector, the combination with a piece of flexible material adapted to be wrapped around the forearm of the wearer, of transverse straps overlying and secured to the underlying portion of the protector, fastening members carried by the respective straps, coacting fastening members secured to the protector, and means ad-

justably engaging the straps for varying 40 the positions of the fastening members thereon relatively to the edges of the protector.

3. In a sleeve protector, the combination with a sheet of flexible material adapted to be wrapped around the arm of the wearer 45 and have its edges overlap thereon, of transverse straps lying adjacent the outer surface of the underlying portion of the protector and attached thereto, a fastening member carried by each strap, a member in sliding 50 engagement with each strap for adjusting the position of the fastening member thereon relatively to one of the edges of the protector, and coöperating fastening members secured at a distance from the other edge of 55 the protector corresponding to the length of the strap.

4. In a sleeve protector, the combination with a flexible piece of material adapted to be wrapped around the forearm of the 60 wearer with its edges overlapped thereon, of a strap secured at one end to the underlying edge of the protector, means for adjustably engaging the strap intermediate of its ends with the overlying portion of the 65 protector, and a two-part separable fastening device, one part carried by the free end of said strap and the other part secured to the protector at a distance from the underlying edge corresponding to the length of 70 the strap.

In testimony whereof I have subscribed my name.

HERMAN SACKS.
